Attorney

UNITED STATES PATENT OFFICE

ROY N. STEWART, OF WASHINGTON, DISTRICT OF COLUMBIA, ASSIGNOR TO AMERICAN DAIRY SUPPLY COMPANY, OF WASHINGTON, DISTRICT OF COLUMBIA, A CORPORATION OF MAINE

COVER-ALL BOTTLE CAP

Application filed November 5, 1930. Serial No. 493,599.

This invention relates to closures for milk bottles or the like and belongs to the type which may be termed cover-all caps, as it is the purpose of such articles to cover the mouth or so-called pouring lip of the bottle to prevent the contamination thereof by reason of general exposure. The object of this invention is the production of a cap of the character stated, having parts of special construction and arrangement whereby it is believed greater resistance to distortion or collapsing of the part which enters the mouth of the bottle is attained, and without interfering in any manner with the feeding of the caps in capping machines. Such caps are ordinarily made of paper or pulp board moistened and formed and treated with molten wax. It is to be understood in this application that no limitation is intended either as to the material, the size or to the processes followed. The applicant holds himself free to employ any known method of making bottle caps now commonly public and used.

The special construction constituting this invention is illustrated in the accompanying drawing, of which Fig. 1 represents the mouth of a milk bottle in section having this invention applied thereto. Fig. 2 is a top view of what is termed the inner portion in this description. Fig. 3 is a bottom or interior view of the parts shown in Fig. 2. Fig. 4 is an edge view of the inner portion much enlarged to show the double ended outer and inner corrugations of the edge. Fig. 5 is a sectional view taken on the broken line 5—5, of Fig. 4. Fig. 6 represents the parts illustrated in Fig. 4 with the external cover portion of the cap applied and the flanges or skirts of the inner and outer portions somewhat compressed.

Throughout the drawing the same number is used to refer to the same part.

Considering Figs. 1, 2 and 3, the bottle 1 has the usual pouring lip 2 and internal seat

3 for the cap. As manufactured, when the milk bottles are taken from the molds while hot and permitted to stand, the vertical wall 4 extending upwardly from the cap seat 3 becomes slightly bulged at the top, but that result is rather to the advantage than otherwise of caps made in accordance with this invention in their operation and acts to additionally resist their displacement. In using these caps it is found that an attempt to lift the cap directly from the top of the bottle is strongly resisted, but that by giving the cap a turning or twisting movement it can be readily taken off by hand and replaced. No implement or skill is demanded.

The external or cover portion 5 has a depending flange or skirt 6 extending downwardly to the pouring lip or as far as may be desired. Skirt 6 lies against the like skirt of the inner portion of the cap and as shown in Fig. 1 the skirt of the inner portion may be shorter than the external skirt 6 to avoid any interference in feeding the caps rapidly in a suitable machine. In the manufacture of the caps in quantities some pressure is applied to finally compress the outer and inner portions fully together as required, and such pressure acts also to smooth the lower circumferential edge of the skirt 6 and the caps are found to feed freely and easily in the capping machine without interruption.

The inner portion of the cap as illustrated in Figs. 2 and 3, has a circular depression bounded outwardly by the vertical wall 7, at the bottom of which is an annular part 8 which may be termed the bottom of the cap. The central part spaced from the wall 7 is a frusto-conical pedestal or raised portion 9, and as shown in Fig. 1 the top of the pedestal centrally supports the cover 5. It is believed that the slanting walls of the cone center of the inner portion and the spacing of the same from the vertical wall 90

7 as set forth, prevents the collapsing or distortion of the wall 7 when the cap is forced into a milk bottle and the wall 7 engages the wall 4 of the bottle. When the 5 cap is placed on a bottle, the wall 7 is very firmly pressed against the wall 4 and the construction of this invention effectually withstands such pressure.

Considering Figs. 4, 5 and 6, recesses 10 are formed in the edge 11 of the enlarged inner portion of the cap as shown, and the recesses 10 have lateral extensions 12 by reason of the double ended outer and inner 15 corrugated construction, illustrated. In Fig. 5 it is shown that that bottom of the outer edge recesses 10 are deepest at the edge and slant outwardly to the rim of the inner portion. Now, if the cover 14 like cover 5 is placed over the inner portion and 20 the whole suitably compressed, a key extension 15 will be forced into the recess 10 and locked therein by further pressure. Therefore, the two portions of the cap not only adhere, but are actually locked together by the construction described.

The operation or application of this invention to milk bottles is the same as that employed in common practice, the invention in this case comprising the structure described.

Having now explained this invention, I claim:—

1. A cover-all bottle cap, comprising an integral inner portion having a dependent 35 peripheral skirt, a vertical wall spaced from said skirt annularly, a central pedestal having the form of a truncated cone with a flat top, the base of the cone being circular and integral with said wall whereby the 40 said wall is stiffened and supported against collapsing when said wall is pressed into the mouth of a milk bottle, and an external cover portion surrounding said skirt and passing over said inner portion, the middle of said cover resting upon the top of the 45 said cone.

2. A cover-all bottle cap comprising a one piece inner portion having a dependent peripheral skirt, a vertical wall annularly 50 spaced from said skirt, a central pedestal having the form of a truncated cone with a flat top, the base of said cone being less in diameter than said wall and integral therewith whereby there is formed an annular 55 bottom to said inner portion, said vertical wall and cone and said annular bottom forming a hollow annular rib whereby said wall is stiffened and supported against collapsing when pressed into the mouth of a 60 milk bottle, and an external cover portion surrounding said skirt and passing over said inner portion, the middle of said cover resting upon the top of said cone.

3. A cover-all bottle cap having a one piece 65 inner portion provided with a depending

outer skirt and a part constructed to enter and to expansively engage the mouth of a milk bottle, said part comprising a vertical circular wall spaced from the skirt and a central pedestal having a base of greater area than the top and inclined side walls, and a cover portion passing over said inner portion, the middle of said cover being supported by the top of the said pedestal.

In testimony whereof I affix my signature.

ROY N. STEWART.
